CLAIM

The ornamental design of a plug for accessory-host interface, as shown and described.

DESCRIPTION

FIG. 1 is a perspective view of a plug for accessory-host interface, showing our new design;

FIG. 2 is a front elevation view of thereof;

FIG. 3 is a left side elevation view thereof;

FIG. 4 is a right side elevation view thereof;

FIG. 5 is a top plan view thereof; and,

FIG. 6 is a bottom plan view thereof.

The broken line showing of the environment is for illustrative purposes only and forms no part of the claimed design.
